REFRIGERATING APPARATUS

Lawrence A. Philipp, Detroit, Mich., assignor to
 Kelvinator Corporation, Detroit, Mich., a corporation of Michigan

Application February 27, 1933, Serial No. 658,722
 Renewed July 15, 1936

17 Claims. (Cl. 62—126)

This invention relates to refrigerating apparatus, and more particularly to refrigerating apparatus of the household type.

One of the objects of my invention is to provide 5 a new and improved arrangement for freezing substances and for cooling circulating air in a refrigerator cabinet.

Another object of my invention is to provide 10 within a refrigerator cabinet refrigerant evaporating means which is arranged and operated without the collection of frost thereon or a slight film of frost is allowed to collect thereon during the on-phase of the refrigerating cycle and is melted off during the off-phase of the refrigerating cycle while at the same time provisions 15 are made for freezing substances, such as ice cubes and the like, and for cooling circulating air in the food storage compartment of the cabinet whereby continuous refrigeration at substantially 20 constant predetermined temperatures is assured and the necessity of periodic inoperative conditions of the system for defrosting is avoided.

Another object of my invention is to provide a 25 new and improved refrigerant evaporator for cooling circulating air in a food storage compartment of a refrigerator cabinet.

Other objects and advantages of the present invention will readily be apparent from the following description and by referring to the accompanying drawing.

In the drawing:

Fig. 1 is a front view in elevation of a refrigerating apparatus embodying features of my invention;

Fig. 2 is a fragmentary, vertical view in cross section of the heat absorbing means embodying features of my invention;

Fig. 3 is a side view in elevation of the relatively small heat capacity refrigerant evaporator forming part of the heat absorbing means;

Fig. 4 is a top plan view in elevation of the heat absorbing means;

Fig. 5 is a fragmentary view in cross section and partly in elevation of a modified form of heat absorbing means; and

Fig. 6 is a view taken along the line 6—6 of Fig. 5.

Referring to the drawing, the numeral 20 designates, in general, a refrigerator cabinet having 50 a food storage compartment 21. Within the food storage compartment there is disposed heat absorbing means designated, in general, by the numeral 23. A refrigerant condensing element 25 is operatively connected to the heat absorbing means 23 by means of a liquid supply conduit 26

and a vapor return conduit 27. The condensing element 25 may be located at any convenient place either within the cabinet or remote therefrom.

Referring more in detail to the drawing, and 5 particularly to Figs. 2, 3 and 4, the heat absorbing means 23 comprises, in general, a refrigerant evaporator 30 which is of relatively small heat capacity and which has a large area exposed to the circulating air within the food storage compartment 21. The evaporator 30 comprises, in 10 general, an outer metallic shell 32 which is of box-like construction and is provided with an open top which is secured to the top insulating wall 33 of the food storage compartment by 15 brackets 34 to prevent the admission of circulating air in the food compartment into the interior of the shell 32. The shell 32 includes vertical side walls 35, bottom wall 37, rear wall 38 and a front wall 40. The front wall 40 is provided 20 with openings 42 of sufficient size for receiving ice making receptacles 45. If desired, the closure member or rear wall 38 may be omitted and the shell 32 disposed in the food storage compartment 21 adjacent the rear wall thereof to 25 prevent circulation of air from the food storage compartment into the interior of the shell 32. The evaporator 30 also includes a pair of embossed sheet metal plates 47, one of each being 30 secured to side walls 35 to provide spaces 48 and 49 for refrigerant. Preferably, the embossed plates 47 are formed to provide serpentine-like passageways for refrigerant between its inner wall and the shell 32. The refrigerant spaces 48 and 49 between the plates 47 and the sheet metal 35 shell 32 are inter-connected by means of a refrigerant conduit 50 which inter-connects said spaces adjacent the lower parts thereof. Liquid refrigerant is supplied to the refrigerant spaces from the liquid supply conduit 26, first into space 40 48 whence it passes through conduit 50 into the refrigerant space 49. In order to increase the heat transfer characteristics of the evaporator 30, I have provided a plurality of U-shaped heat absorbing fins 51. These fins are vertically disposed in parallel relation on each side of the evaporator adjacent the refrigerant spaces 48 and 49. Preferably, the fins are welded to the shell 32.

The heat absorbing means 23 also includes a 50 relatively large heat capacity refrigerant evaporator or low temperature evaporator 55 which is disposed entirely within the confines of the relatively small heat capacity evaporator 30 so that its exposed surfaces will be exposed to substan- 55

tially non-circulating air. This arrangement either substantially or entirely avoids the necessity of periodically defrosting the low temperature evaporator 55. The low temperature evaporator 55 includes an outer sheet metal shell 57 and an inner sheet metal shell 59 suitably secured together as by welding adjacent their edges and at various contacting points between the edges. These shells are formed substantially in the shape of a U and the outer shell being corrugated as at 61 to provide spaces for the passage of refrigerant between said shells. The inner shell is provided with a pair of arcuate portions 62 adjacent the upper opposite extremities thereof to provide refrigerant headers 63 for liquid and gaseous refrigerant. The headers 63 are interconnected by means of conduit 64 to which the vapor return conduit 27 is connected. Liquid refrigerant is delivered to the low temperature evaporator 55 through a conduit 67 which is connected to the outlet end of the relatively small heat capacity evaporator 30. Both liquid and gaseous refrigerant passes from the evaporator 30 through conduit 67 into the low temperature evaporator 55. The gaseous refrigerant is withdrawn from the headers 63 and conduit 64 through the vapor conduit 27. Suitable shelves 71 are provided within the ice freezing zone 73 of evaporator 55 to support the ice trays 45.

30 The refrigerant condensing element comprises, in general, a compressor 70, motor 72 for operating the compressor, condenser 74, and a high side float mechanism 75. The compressor withdraws evaporated refrigerant from the heat absorbing means through conduit 27, compresses the gaseous refrigerant and delivers it to the condenser wherein it is liquefied and from which it is delivered to the high side float mechanism. Liquid refrigerant is supplied to the heat absorbing means through conduit 26 under the control of float mechanism 75.

35 Preferably, the condensing element is intermittently operated for maintaining substantially constant predetermined temperatures in the heat absorbing means. In order to control the operation of the condensing element, I have provided an automatic switch 80 which is actuated by expansible bellows 82 and a thermostatic fluid containing bulb 85 in response to changes in temperatures in the relatively small heat capacity evaporator 30 for connecting and disconnecting the motor to and from the power mains 81. Preferably, the bulb 85 is soldered to a side wall of the evaporator 30 adjacent the refrigerant space 48.

40 From the foregoing, it will be noted that the low temperature evaporator 55 is disposed within the confines of the evaporator 30 which is sealed to a wall of the food storage compartment. Under these conditions, none of the exposed surfaces are arranged so that the circulating air in the food compartment will contact therewith. Only the substantially non-circulating air within shell 32 can contact with the low temperature evaporator. Thus, it is unnecessary to temporarily interrupt the normal cyclic operation of the condensing element to defrost the low temperature evaporator as the accumulation of frost thereon is unlikely. Thus, insofar as the low temperature evaporator is concerned, continuous refrigeration of a substantially constant predetermined value is assured.

45 In order to avoid the necessity of interrupting the refrigerating effect of the relatively small heat capacity evaporator, I have arranged the

thermostatically controlled switch 80 so that the condensing element is operated in such a manner that the demand for refrigeration by the evaporator 30 is supplied in an amount which permits the evaporator to operate at temperatures which would be unlikely to cause the formation of frost on its exposed surfaces due to the deposit of moisture from the circulating air. If desired, the switch 80 may be set so that only a slight film of frost collects thereon during the on-phase of the refrigerating cycle and is melted off during the off-phase of the refrigerating cycle. By providing a relatively small heat capacity refrigerant evaporator which has a large area exposed to the circulating air, it may be operated under these conditions and maintain proper temperatures within the food compartment for the preservation of foods stored therein. Thus, continuous refrigeration of a substantially constant, predetermined value in the evaporator 30 is assured. 20

In an apparatus of the type hereinbefore described, the moisture contained in the circulating air is deposited on the walls of the evaporator and whether the evaporator is permitted to accumulate a slight film of frost between cycles 25 or whether it operates so that no frost forms thereon the temperature is low enough to accumulate moisture on the side walls adjacent the spaces 48 and 49 and on fins 51. In order to carry off the drip water received from the fins 51 and sides 35 30 of evaporator 30, I have provided troughs 90 immediately below the fins 51 and at the lowermost parts of side walls 35. Preferably, the troughs 90 are formed integrally with a sheet metal member 92 which serves to clamp a slab of insulation 94 to the bottom wall 37 of the evaporator 30. This insulation prevents the deposit of moisture on the lowermost part of the evaporator 30. Thus, it will be noted that the drip water from the side walls is taken care of by troughs 90, and 40 it will also be noticed that moisture is not deposited on the bottom wall of the relatively small heat capacity evaporator. If desired, the troughs 90 may be interconnected by a conduit (not shown) which may be used for carrying off the 45 drip water to a suitable drain.

Referring now to Figs. 5 and 6, there is shown a modified form of heat absorbing means which comprises, in general, a relatively small heat capacity evaporator 100, which is constructed in all respects like evaporator 30 and is operated under the control of bulb 102 (which may be connected to bellows 82) in a like manner as is evaporator 30. The evaporating means used for freezing ice cubes and the like in this instance comprises three 55 refrigerated plate type evaporators 105. Liquid refrigerant leaves evaporator 100 through conduit 110 whence it passes into the lowermost plate evaporator 105 and from whence it is delivered into the intermediate plate evaporator 105 60 through conduit 112, and from the intermediate plate it is delivered to the uppermost plate through conduit 114. Liquid refrigerant is supplied to evaporator 100 through conduit 126, and evaporated refrigerant is withdrawn from the uppermost plate evaporator 105 through conduit 127. Conduits 126 and 127 correspond to conduits 26 and 27 and may be connected to the condensing element 25 in a like manner as conduits 26 and 27 are connected thereto. The plates 105 70 are adapted for supporting ice trays and provide means for rapidly freezing the water in the trays. 75

From the foregoing, it will be apparent that I have provided refrigerant evaporating means which I have arranged in such a manner that it

operates without the collection of frost thereon or with a slight film of frost collecting thereon only between cycles, while at the same time provisions are made for freezing substances, such as 5 ice cubes and the like, and for cooling circulating air in the food storage compartment of the cabinet whereby continuous refrigeration at substantially constant predetermined temperatures is assured and the necessity of periodic inoperative 10 conditions of the system for defrosting is avoided. Inasmuch as the formation of a blanket of frost or ice on the surfaces of an evaporator acts as an insulating medium to the transfer of heat, it will also be apparent from the foregoing 15 that the system described herein operates at maximum efficiency and continuous refrigeration is furnished without interrupting the refrigerating effect of the heat absorbing means to free frost and ice therefrom.

20 Although only a preferred form of the invention has been illustrated, and that form described in detail, it will be apparent to those skilled in the art that various modifications may be made therein without departing from the spirit of the 25 invention or from the scope of the appended claims.

What I claim as my invention is:

1. Refrigerating apparatus comprising, in combination, a cabinet having a food storage compartment, a refrigerant evaporating element disposed in said compartment for cooling circulating air therein, a second evaporating element for maintaining relatively low temperatures for freezing substances, said second evaporating element 30 being shielded from the path of circulating air in the food storage compartment by said first named evaporating element to prevent the deposit of moisture on said low temperature evaporating element from the circulating air, an intermittently operating refrigerant condensing element associated with said evaporating elements for maintaining said evaporating elements substantially flooded with liquid refrigerant, and means directly associated with said first named evaporating 35 element for controlling the operation of said condensing element, said means controlling the on and off phases of the refrigerating cycle in such a manner that frost does not accumulate on the first named evaporating element at least part of 40 the time.

2. Refrigerating apparatus comprising a relatively small heat capacity evaporator adapted to be positioned in a cabinet for cooling circulating air therein and having a relatively large area 45 exposed to the circulating air in the cabinet, a unitary relatively large heat capacity evaporator disposed within the confines of the small heat capacity evaporator so that its exposed area will be exposed to substantially non-circulating air, 50 means for maintaining a substantially constant quantity of liquid refrigerant in each of said evaporators, and means directly responsive to changes in temperature in said first named evaporator for controlling said means.

3. Refrigerating apparatus comprising, in combination, a cabinet having a food storage compartment, a box-like refrigerant evaporating element having an open top secured to an insulated wall in said compartment, said evaporating element including an insulated bottom wall, a front wall having an opening, means associated with each side wall to provide spaces for refrigerant, closure means for the rear of said element and a refrigerant conduit interconnecting 55 said side walls, a refrigerant evaporating ele-

ment disposed within the confines of said box-like evaporating element arranged for receiving an ice making receptacle through the opening in the front wall of the box-like element, and means for supplying refrigerant to said elements. 5

4. A refrigerant evaporating element comprising a sheet metal shell including vertical walls and a bottom wall, one of said vertical walls having an opening of sufficient size to receive an ice making receptacle, an embossed sheet metal plate 10 cooperating with one of said vertical walls to provide a space for refrigerant, a second embossed sheet metal plate cooperating with an opposite wall to provide an additional space for refrigerant, and a refrigerant conduit interconnecting 15 said spaces adjacent the lower parts thereof.

5. A refrigerant evaporating element comprising a sheet metal shell including vertical walls and a bottom wall, one of said vertical walls having an opening of sufficient size to receive an ice 20 making receptacle, an embossed sheet metal plate cooperating with one of said vertical walls to provide a space for refrigerant, a second embossed sheet metal plate cooperating with an opposite 25 wall to provide an additional space for refrigerant, a refrigerant conduit interconnecting said spaces adjacent the lower parts thereof, and a relatively low temperature refrigerant evaporator disposed within said shell for freezing the 30 contents of said receptacle.

6. A refrigerant evaporating element comprising a sheet metal shell including vertical walls and a bottom wall, one of said vertical walls having an opening of sufficient size to receive an ice 35 making receptacle, an embossed sheet metal plate cooperating with one of said vertical walls to provide a space for refrigerant, a second embossed sheet metal plate cooperating with an opposite wall to provide an additional space for 40 refrigerant, a relatively low temperature refrigerant evaporator disposed within said shell for freezing the contents of said receptacle, means for delivering liquid refrigerant to one of said spaces, a conduit interconnecting said spaces for 45 delivering liquid refrigerant from said space to the other, means for carrying off liquid and gaseous refrigerant to the low temperature evaporator, and means for withdrawing evaporated refrigerant from the low temperature evaporator. 50

7. Refrigerating apparatus comprising, in combination, a cabinet having a food storage compartment, a box-like refrigerant evaporating element having an open top secured to a wall of said compartment, said evaporating element including an insulated bottom wall, vertical walls, independent embossed plates cooperating only with the two opposite side walls to provide spaces for refrigerant, a refrigerant conduit interconnecting said spaces at the lower parts thereof, 60 fins on said side walls adjacent said plates, and troughs associated with said elements for receiving moisture deposited from said fins.

8. Refrigerating apparatus comprising a refrigerant evaporator adapted to be positioned in a cabinet for cooling circulating air therein and having a relatively large area exposed to the circulating air in the cabinet, a refrigerant evaporator disposed within the confines of the first named evaporator so as to be shielded from said 65 circulating air, a liquid refrigerant conduit interconnecting said evaporators for conducting liquid refrigerant from one evaporator to the other, means for maintaining a substantially constant quantity of liquid refrigerant in said 70 evaporators, and a refrigerant conduit interconnecting said side walls, a refrigerant evaporating ele-

evaporators, and a thermostat responsive to changes in temperatures in said first named evaporator and arranged to so control said means as to operate the first named evaporator 5 at least part of the time above a frost forming temperature and the second evaporator constantly at a freezing temperature.

9. Refrigerating apparatus comprising a sheet metal shell having an opening in a wall thereof, 10 a sheet metal member cooperating with a second wall of said shell to provide a space for refrigerant, a refrigerant evaporator disposed within the confines of said shell and having provisions for receiving an ice making receptacle through 15 said opening, means for maintaining a substantially constant level of liquid in said space for refrigerant and in said evaporator, and a thermostat thermally associated with the refrigerant in said space for controlling said means.

20 10. A refrigerant evaporating element comprising a sheet metal shell including vertical walls and a bottom wall, one of said vertical walls having an opening of sufficient size to receive an ice making receptacle, sheet metal material cooperating 25 with opposed vertical walls to provide spaces for refrigerant, a refrigerant conduit interconnecting said spaces, and a relatively low temperature refrigerant evaporator disposed within said shell for freezing the contents of said receptacle.

30 11. A refrigerant evaporating element comprising a sheet metal shell including vertical walls and a bottom wall, one of said vertical walls having an opening of sufficient size to receive an ice making receptacle, sheet metal material cooperating 35 with opposed vertical walls to provide spaces for refrigerant, a refrigerant conduit interconnecting said spaces, a low temperature refrigerant evaporator disposed within said shell for freezing the contents of said receptacle, and insulating material associated with said bottom 40 wall.

12. Refrigerating apparatus comprising, in combination, a cabinet having a food storage compartment, a box-like refrigerant evaporating 45 element constructed of sheet metal material and having an open top secured to an insulated wall in said compartment, said evaporating element having an open front, sheet metal means associated with opposed side walls to provide spaces for refrigerant, a refrigerant evaporating element disposed within the confines of said box-like 50 element and being arranged for receiving an ice making receptacle through said open front of the box-like element, and means for supplying 55 refrigerant to said elements.

13. Refrigerating apparatus comprising, in combination, a cabinet having a food storage compartment, a box-like refrigerant evaporating element constructed of sheet metal material and 60 having an open top secured to an insulated wall in said compartment, said evaporating element including a front wall having an opening, sheet metal means associated with each side wall to provide spaces for refrigerant, and ice tray, heat

absorbing means disposed within the confines of said element and being arranged for supporting said ice tray, a tray front secured to said tray, said tray front being arranged to close said opening when supported by said means, and means for 5 supplying refrigerant to said element and heat absorbing means.

14. Refrigerating apparatus comprising, in combination, heat absorbing means including a refrigerant evaporating element adapted to be 10 positioned in a compartment for cooling circulating air therein and having a large area exposed to said circulating air, and said heat absorbing means including a second refrigerant evaporating element shielded from said circulating 15 air whereby the moisture in said circulating air is not deposited on said second element and the heat of the circulating air does not warm up said second element as rapidly as the first named element, means for delivering liquid refrigerant 20 first to said first named element and then both liquid and gaseous refrigerant from said first element to said second element, and thermostatic means associated with said first element for controlling the operation of said apparatus in such 25 a manner that frost does not accumulate on said first element at least part of the time.

15. A refrigerating system of the flooded type comprising a refrigerant evaporating element adapted to be positioned in a compartment for 30 cooling circulating air, a second refrigerant evaporating element for freezing substances, a refrigerant condensing unit associated with said elements, a high side float mechanism for controlling the flow of refrigerant to said first element, conduit means for conducting the flow of both liquid and gaseous refrigerant to the second element after the refrigerant has passed through 35 said first element, and means directly responsive to the condition of said first element for controlling the operation of said condensing unit.

16. A refrigerating system of the flooded type comprising a refrigerant evaporating element adapted to be positioned in a compartment for 45 cooling circulating air, a second refrigerant evaporating element for freezing substances, a refrigerant condensing unit associated with said elements, mechanism for controlling the flow of refrigerant to said first element, conduit means for conducting the flow of both liquid and gaseous 50 refrigerant to the second element after the refrigerant has passed through said first element, and means directly responsive to the condition of said first element for controlling the operation 55 of said condensing unit.

17. A refrigerant evaporating element of the type adapted to be positioned in a compartment for cooling circulating air therein, comprising refrigerant containing walls exposed to the circulating air in the compartment and a bottom 60 wall insulated so that cooling of the circulating air is accomplished only by said other walls.
